UNITED STATES PATENT OFFICE.

FREDERICK K. WRIGHT, OF SYRACUSE, NEW YORK, ASSIGNOR TO R. E. DIETZ COMPANY, OF NEW YORK, N. Y.

LANTERN.

No. 895,133.

Specification of Letters Patent.

Patented Aug. 4, 1908.

Application filed September 9, 1907. Serial No. 391,891.

To all whom it may concern:

Be it known that I, FREDERICK K. WRIGHT, a citizen of the United States, residing at Syracuse, in the county of Onondaga and State of New York, have invented a new and useful Improvement in Lanterns, of which the following is a specification.

This invention relates to loops, staples, bearings, posts and similar fixed parts which are used in lanterns for confining or guiding movable parts, for instance, to the guide loops or staples which are secured to the side tubes of tubular lanterns for confining and guiding the upright wires or rods of the vertically movable globe frame or support to the bearings in which the lifting levers are journaled, and to the posts which project upwardly from the base portion of the lantern and enter an opening in the detachable globe plate for preventing the latter from turning on the burner. These loops and other devices have usually been secured to the tubes by soldering.

The object of this invention is to secure such devices to the tubes or other supports by more durable and reliable means and without requiring the expensive operation of soldering.

In the accompanying drawings, consisting of two sheets: Figure 1 is an elevation of a tubular lantern in which the guide loops are secured to the tubes by this invention. Fig. 2 is a fragmentary inside elevation of the tube before securing the loop thereto. Fig. 3 is a fragmentary vertical section of one of the tubes and a loop secured thereto. Fig. 4 is a horizontal section in line 4—4, Fig. 3. Fig. 5 is a similar horizontal section, showing the loop in position to be secured to the tube. Fig. 6 is a perspective view of the loop before it is applied to the tube. Fig. 7 is a front elevation of the lower portion of a lantern in which the lever bearing is secured to the tube by this invention. Fig. 8 is a vertical section in line 8—8, Fig. 7, on an enlarged scale. Fig. 9 is a fragmentary sectional elevation, showing a post secured to the lower portion of the lantern by this invention.

Like reference characters refer to like parts in the several figures.

A represents the side tubes forming part of the rigid frame of a tubular lantern and B the upright side wires or rods forming

part of the globe frame which is movable vertically in the rigid lantern frame in a well known manner.

C represents the guide loops which are secured to the tubes on the inner sides thereof and project inwardly for confining and guiding the upright wires or members B of the globe frame.

The body 20 of each loop has the form of a bow, arch or horse shoe and is provided at its ends with attaching shanks 21 which are adapted to be inserted into vertical slots 22 formed side by side in the inner wall of the tube or other support. The loop is provided at the bases of the shanks with upright shoulders 23, preferably arranged, as shown, above and below the shanks. The loop is made of material which is so pliable or flexible that the body of the loop can be compressed or partially flattened after the shanks have been inserted into the slots and which is so stiff or strong that it retains its shape after the body has been so compressed or flattened. Sheet brass or tinned sheet steel is suitable for this purpose.

In the original form of the loop, which is represented in Figs. 5 and 6, the body of the loop is horse-shoe shaped or arched and the attaching shanks or lips extend from the ends of the body with divergence or such an angle that the shanks can be thrown against the internal side of the inner wall 24 of the tube by compressing or partially flattening the arch or horse shoe, as represented in Fig. 4. After the attaching shanks have been inserted into the slots of the tube the body of the loop is compressed, pinched or flattened sufficiently to throw the shank or lips against the internal side of the inner wall of the tube. The loop is now rigidly secured to the tube by the stop shoulders 23 bearing against the external side of the wall 24 and the attaching shanks or lips bearing against the internal side thereof. The required compressing or flattening of the loop brings the two branches or end portions of the loop closer together than in the original form of loop but does not flatten the loop to such an extent as to interfere with the free movement of the wire C or other movable part of the loop. The loop is attached to the tube by this means in a very simple and durable manner and the expensive operation of soldering is rendered unnecessary.

In the construction represented in Figs. 7 and 8, the bearing 30 in which the lifting lever 31 is journaled is secured to the tube by deflected attaching shanks 32.

5 In the construction represented in Fig. 9, the post 40, which enters in a well known manner an opening in a detachable globe plate 41 for holding the latter against turning, is secured to the top plate 42 of the lower 10 air chamber by deflected attaching shanks 43.

I claim as my invention:

1. The combination of a supporting tube provided with slots and a flexible loop or staple arranged on the outer side of said tube and bearing against the same, said loop or staple having diverging attaching shanks which project through said slots into said tube and having outside of said tube compressible portions, whereby when said portions are pressed 15 toward each other said attaching shanks are thrown against the internal surface of the 20

tube, thereby securing the loop or staple rigidly to the tube, substantially as set forth.

2. The combination of a supporting tube provided with slots and a flexible loop or staple which is provided with stop shoulders which bear against the outer side of said tube and with diverging shanks which project into the tube through said slots, said loop or staple being provided outside of said shoulders with 25 compressible portions, whereby when said portions are pressed toward each other said attaching shanks are thrown against the internal surface of the tube, thereby securing the loop or staple rigidly to the tube, substantially 30 as set forth.

Witness my hand in the presence of two subscribing witnesses.

FREDERICK K. WRIGHT.
